ABSTRACT OF THE DISCLOSURE

The apparatus described herein includes a tank for storing a liquid and a granular material, such as water and sand, under an internal hydraulic pressure. A pipeline extends from a liquid pump to an outlet having a nozzle for emitting a stream of liquid under pressure. The pipeline downstream from the pump includes first branch line including a perforate pipe section extending generally horizontally within the tank and below the upper level of granular material within the tank. The pipeline includes a second branch line in parallel with the first branch line so that a portion of the flow from the pump can bypass the tank. Flow control valves are provided in both branch lines for regulating the proportion of total flow through each branch and thereby the concentration of grit in the flow at the nozzle. The tank is provided with a top filler opening for adding granular material and a closable air vent to permit filling the tank with liquid at line pressure.

As liquid flows from the pump through the perforate pipe section with the tank under an internal hydraulic pressure approximating the line pressure, granules from the tank pass through the perforations in the perforate pipe section and become entrained in the flow, which carries them to the nozzle where they are discharged in a high pressure liquid spray.

BACKGROUND OF THE INVENTION

(A) Field of the invention

This invention relates to hydraulic grit dispensing apparatus, such as, for example, hydraulic sandblasting equipment, used for cleaning and removing paint from objects and for etching.

(B) Description of the prior art

In prior hydraulic sandblasting equipment and related hydraulic grit dispensing apparatus a venturi or jet spray principle has been utilized most commonly to mix the gritty material with a flow of liquid to be sprayed. For example, Umbrecht et al., U.S. Pat. 3,150,467 illustrates the use of a jet spray device and Moore U.S. Pat. 3,267,615 illustrates the use of a venturi device for this purpose. However, both types of equipment are relatively complex, expensive, inflexible, and difficult to control. A further disadvantage of a venturi device is that it is subject to blockage and rapid wear by the grit material. Another prior type of hydraulic grit dispensing apparatus utilizes a pump to suck a suspension of sand and water from a reservoir, but such apparatus requires means such as an agitator to maintain the sand in suspension in the water and also draws the sand and water mixture through the pump, thereby subjecting the pump to extreme wear. Such an arrangement is shown, for example, in U.S. Pats. 1,966,571; 2,573,917.

SUMMARY OF THE INVENTION

The apparatus of the present invention overcomes the problems of expense, complexity, wear, and lack of flexibility of the prior art in that it comprises a liquid pressure system including simply a pressure vessel and a pipeline having a perforate pipe section extending within the vessel through which liquid is pumped to a discharge nozzle downstream from the vessel. When the vessel is filled with liquid under a hydraulic pressure approximating line pressure and at least partially filled with the granular material to be dispensed, flow through the perforate pipe section, which may be of constant diameter throughout its length, will induce granules within the vessel to enter the flow, which carries the granules to the nozzle where they are dispensed in a liquid spray. The concentration of grit in the flow can be varied by varying the rate of flow or the size of the perforations, or by diverting a variable portion of the flow so that it bypasses the perforate pipe section.

20 BRIEF DESCRIPTION OF THE DRAWINGS

The foregoing and other objects and advantages of the present invention will become more apparent from the following detailed description which proceeds with reference to the accompanying drawings wherein:

25 FIG. 1 is a side elevational view, mostly in section, of one form of apparatus in accordance with the present invention;

FIG. 2 is a side elevational view, partly in section, of 30 a second form of apparatus in accordance with the invention;

FIG. 3 is an enlarged partial sectional view showing the perforate pipe section of FIG. 2 and its connection to the tank of the apparatus; and

35 FIG. 4 is a horizontal sectional view through a third form of apparatus in accordance with the invention.

DETAILED DESCRIPTION

FIG. 1 embodiment

40 With reference to the drawings, FIG. 1 illustrates one form of apparatus in accordance with the invention, including a generally cylindrical pressure vessel 10 having a flat bottom 12 and an open top closed by a cover 14. The cover is secured to an annular flange 16 of the vessel 45 by bolts 18. A gasket 20 positioned between the lid and the flange provides a pressure tight seal. The cover has a filler opening 22 through which the vessel may be filled with a granular material such as the sand 24 shown within the vessel. The filler opening is normally closed during 50 operation of the apparatus by a screw type filler cap 26. An air vent pipe 28 extends through another opening in the cover and is closable by a manually operated valve 30.

The apparatus also includes a liquid pressure system 55 including a pressure liquid passage means extending from a source of liquid under pressure to an outlet opening. The passage means includes a pipeline indicated generally at 32 connected at one end to a liquid pump 34 and at the other end to a nozzle 36 at the outlet. The pipeline includes a primary pipe section 32a extending from the pump to a T coupling 38 just upstream from the vessel. At this coupling the pipeline diverges into two branch pipe sections, one 32b extending horizontally above the vessel to bypass the same, and the other 32c passing vertically downwardly through an opening 40 in the cover and into the vessel. Branch section 32c terminates near the bottom of the vessel at a 90° elbow 42 to which is connected a perforate pipe section 44, which extends from one side of the tank to an opposite side thereof just above bottom 12, finally terminating at another 90° elbow 46. A vertical pipe section 32d extends upwardly from elbow 46 and through cover 14 to another T coupling 48. Cou-

pling 48 is also the downstream terminus of branch pipe section 32b. From T 48, the flow through both branches merges and flows downstream through a common outlet pipe section 32e, which is coupled at 50 to a length of flexible hose 52 having nozzle 36 at its outlet end.

Branch pipe section 32b bypassing the tank includes a manually operable regulating and shut off valve 54. A second manually operable regulating valve 56 is provided in branch line 32c leading into the tank to the perforate pipe section 44. These two valves are used to regulate and vary the flow through each of the two branches. In fact, the valves can be used to send all of the flow through either one of the branches, if desired.

OPERATION

To operate the apparatus of FIG. 1, filler cap 26 is removed and the vessel is at least partially filled with sand or some other desired granular material, depending on the end use to which the apparatus is to be put. Then the filler cap is replaced. Valve 30 on the vent pipe is opened, valve 54 closed and valve 56 opened so that the full flow initially passes through perforate pipe section 44 and into the vessel. Nozzle 36 is also preferably closed so that the vessel fills rapidly with liquid flowing through the perforations 58 in pipe section 44. After the vessel is filled with liquid, valve 30 is closed so that the internal hydraulic pressure of the vessel approximates that of the line. Valves 54 and 56 are adjusted so that the desired proportion of the total flow passes through perforate pipe section 44. Thereafter, upon continued flow through branch 32c and the perforate pipe section, granular material flows from the vessel, through the perforations and into the flow, where it becomes entrained to be carried to the nozzle. At T 48 the grit-carrying flow is merged with any additional flow from bypass line 32b.

Under static hydraulic conditions pressure within the perforate pipe section and within the vessel would be equal. However, as liquid flows through the perforate pipe section to the nozzle, a slight pressure differential is created at the perforations due to the flow through the perforate pipe section. It is believed that the slight pressure reduction within the pipe coupled with the force of gravity acting on the sand causes the sand to gravitate toward and into the perforate section. A very satisfactory intermixing occurs within the perforate section despite the absence of any venturi or jet device. The grit entraining action continues until the level of granular material within the vessel approaches the bottom thereof. The concentration of sand or other grit in the spray is controlled by varying the proportion of flow through the perforate pipe section, the greater the proportion of the total flow through the perforate pipe section, the higher the concentration of grit in the total flow at the nozzle.

The concentration of grit in the final spray can also be controlled by varying the size of perforations 58 in the perforate pipe section. The larger the perforations, the greater will be the rate of flow of granules into the perforate pipe section. However, it has been found that, in general and depending on the size of the granules, the tendency of the perforate pipe to clog is increase with an increase in the size of the perforations beyond certain limits.

EXAMPLE

For example, in one test device made in accordance with the embodiment of FIG. 1 and operated with ordinary sand, the perforate pipe section had a three-quarter inch inside diameter with perforations spaced throughout the circumference of the perforate pipe section. It was found that the apparatus worked best with perforations ranging in size from one-sixteenth inch to one-quarter inch in diameter. The aforesaid test apparatus was operated with a pump delivering water at its outlet under pressure of 450 p.s.i. at twenty gallons per minute (g.p.m.). Pipe having a three-quarter inch inside diameter

was used throughout the system with a hose of one-half inch inside diameter and a three-sixteenths inch nozzle. The vessel itself had an inside diameter of twelve inches and an inside height of eighteen inches. The outlet orifice of the pump had a one-half inch inside diameter. With both valves 54 and 56 wide open, the apparatus delivered a spray at the nozzle having a concentration of approximately 2% sand, by weight.

FIGS. 2 and 3 embodiment

FIGS. 2 and 3 illustrate another, commercial form of the apparatus including a high strength steel tank 100 having curved upper and lower ends 102 and 104, respectively, with a filler opening 106 and filler cap 108 at the upper end and a drain opening 110 and drain cap 112 at the lower end. The upper end also includes a closable air vent pipe 114.

In this embodiment a straight perforate pipe section 116 is connected at its opposite ends to axially aligned externally threaded sleeve couplers 118, 120 at opposite sides of the tank near the bottom.

More specifically with reference to FIG. 3, couplings 118, 120 are threaded into bosses 121, 122, respectively, welded to the outside of the tank surrounding axially aligned openings 123, 124 therein. Coupling 120 is internally threaded to receive an externally threaded end 125 of perforate pipe 116. The opposite coupling 118 has a smooth but slightly tapered bore at 126 which snugly receives a complementary, tapered end 127 of perforate pipe 116.

An inlet pipe section 130 is connected as by welding at its downstream end to coupling 120 and is connected at its upstream end to a pump (not shown). An outlet pipe section 132 is connected at its upstream end to coupling 118 on the tank, and at its downstream end to a flexible hose as shown in the FIG. 1 embodiment.

A branch pipe section 134, which is imperforate and corresponds to the branch section 32b of FIG. 1, also passes through the tank, bypassing perforate section 116. In fact, the greater length 136 of branch line 134 is a single length of pipe welded to opposite sides of the tank. The opposite ends of pipe 136 are threaded and project outside the tank so that they can be coupled to the remaining portions of the branch 134 by suitable couplings. Bypass section 134 is connected to the main inlet and outlet pipes 130 and 132 at T connections 138 and 139, respectively. Both the bypass branch 134 and the branch including perforate pipe section 116 are provided with regulating valves 140, 142, respectively, outside the tank to control the flow rate through both branches. Another valve 144 is provided downstream from the perforate pipe 116 but upstream from T 139 to prevent the drawing of sand into outlet 132 when a gritless flow of fresh water through bypass 134 is desired.

The operation of the tank of FIG. 2 is the same as that described with respect to FIG. 1.

As one example of the commercial form shown in FIG. 2, the tank has a thirty gallon capacity with a sixteen inch outside diameter and a thirty inch height throughout its cylindrical extent. The tank is made of steel and is capable of withstanding a working pressure of 600 p.s.i. The filler opening has a three inch diameter, and the drain opening has a two inch diameter. All piping, including the perforate pipe section, is three-quarter inch stock. The openings in the perforate pipe section are of three-sixteenths inch diameter and spaced apart longitudinally on three-quarter inch centers. There are four rows of openings spaced circumferentially about the pipe, with the holes of adjacent rows being staggered with respect to one another.

It is to be understood that the foregoing examples are illustrative only and not intended as limitations on the invention except as they may be included in the claims. The perforate pipe sections are of constant diameter throughout their lengths, although this is not essential, the sig-

nificance being that the apparatus does not need to depend on any venturi action to induce the sand to enter the perforate pipe section. Although the perforate pipe sections in the two illustrated embodiments extend horizontally, it should be understood that such pipe sections could extend at a slight inclination to the horizontal so long as they paralleled approximately the bottom of the tank. In this regard a generally horizontally disposed perforate pipe section is much preferred to a generally upright perforate pipe section. The latter would drastically reduce the efficiency of the apparatus because as the level of sand within the tank lowered, it would expose progressively more perforations above the sand and thereby reduce progressively the concentration of sand in the spray during any single blasting operation. Continual adjustment and frequent refilling would be required to correct the situation.

FIG. 4 EMBODIMENT

Although the embodiments of FIGS. 1 and 2 show the use of only a single perforated pipe section, it should be understood that if a higher concentration of grit in the spray is desired than could be obtained with a single perforate pipe section, several perforate pipe sections could be placed in parallel with each other within the tank, with the flow through each of the parallel pipe sections eventually being merged at a common outlet pipe section. For example, FIG. 4 illustrates somewhat schematically a pressurized tank 150 similar to that of FIG. 2 partially filled with sand or other cleansing agent and water. A pipe 152 leading from a pump (not shown) divides at 153, into a pair of parallel pipes 154, 155 which then extend into tank 150. The parallel pipes include perforate pipe sections 156, 157 within the tank. Parallel pipes 154, 155 then extend outwardly through the tank and merge again at 158 into a single outlet pipe 160 which leads to a nozzle or other outlet opening.

The apparatus as described would be used most commonly with sand and water. However it will be understood that any liquid and granular material could be used successfully in the apparatus of the present invention. For example, the apparatus has been used successfully with sawdust in the tank, using water as the carrier. Thus, it is not necessary that the granular material be heavier than the liquid carrier, although such is preferred for optimum performance. In fact, materials soluble in water, such as detergents, have been used successfully in the tank, and it is believed that the apparatus could also be used to dispense a mixture of two dissimilar liquids, one, such as water, as the carrier, and another, such as an insecticide, as the material to be dispensed from the tank. However, the apparatus is primarily intended for use in dispensing granular material in a high liquid pressure blast for cleaning purposes.

A particular advantage of the FIG. 2 form is that if a perforate pipe section having larger openings is desired, one perforate pipe section can be replaced easily and quickly by another having openings of the desired size.

METHOD

Summarizing the method of the present invention, it contemplates the flow of a continuous stream of liquid carrier through an internally pressurized tank filled with both a mixture of granular material, preferably having a greater density than the liquid, and more of the liquid under pressure approximating the pressure of the stream except for the slightly reduced pressure of the stream due to its velocity. The stream flow within the tank passes beneath but adjacent to the granular material and is separated therefrom by a foraminous boundary layer which controls the rate of entrainment of granular material in the stream.

Having illustrated and described three preferred embodiments of the invention, it should be apparent to those having skill in the art that the same permits of modifica-

tion in arrangement and detail. We claim as our invention all such modifications as come within the spirit and scope of the following claims:

5. A dispensing apparatus including a closed vessel containing a fluent nongaseous material and a pipeline extending from a source of pressurized liquid carrier through said vessel to an outlet opening, characterized by said vessel being fluid pressure tight and under an internal liquid pressure when the apparatus is in operation, and said pipeline including a perforate pipe section extending within an interior portion of said vessel containing said fluent material, said perforate section providing a liquid flow path of substantially constant cross sectional area throughout the length thereof and through said fluent material so that the normal flow of said liquid carrier through said perforate section in flowing continuously from said source to said outlet entrains some of said fluent material in said liquid and carries the same to said outlet.

20. Hydraulic grit-dispensing apparatus comprising: a vessel including means for internally pressurizing said vessel, said vessel including means for adding a granular material thereto,

25. a liquid pressure system including continuous passage means extending from a source of liquid under pressure to an outlet,

30. said passage means including a perforate pipe section extending generally horizontally within a lower portion of said vessel downstream from said source and upstream from said outlet, whereby with said vessel at least partially filled with granular material and with liquid, the flow of liquid through said perforate pipe section induces the flow of granules from said vessel into said section where they become entrained in flowing liquid and carried therein to said outlet.

35. 3. Apparatus according to claim 2 wherein said perforate pipe section is of substantially constant inside diameter throughout the length thereof whereby there is a substantial absence of venturi action inducing the entraining of granules in the flow within said section.

40. 4. Apparatus according to claim 2 wherein said vessel includes a selectively closable air vent which permits when open the filling of said vessel with liquid from said perforate pipe section and which when closed places the vessel under a pressure approximating the pressure of the flow within said perforate pipe section.

45. 5. Apparatus according to claim 2 wherein said passage means includes an imperforate branch pipe section in parallel with said perforate section so that a portion of the flow through said passage means bypasses said perforate pipe section, said passage means including a passage section downstream from said perforate and branch pipe sections rejoining the flows from said branch and perforate pipe sections upstream from said outlet.

50. 6. Apparatus according to claim 5 wherein said passage means includes means for regulating the proportion of the total liquid flow passing through said perforate and branch pipe sections.

55. 7. Apparatus according to claim 6 wherein said means for regulating flow includes a first valve means in said branch pipe section and a second valve means in a pipe section in parallel with said branch pipe section and connected to said perforate pipe section.

60. 8. Apparatus according to claim 2 wherein said perforate pipe section extends through said vessel from one side thereof to another and wherein said apparatus includes means for fastening said perforate section to said vessel at said sides thereof.

65. 9. Apparatus according to claim 8 wherein said perforate pipe section is threaded at its opposite ends and said vessel includes threaded portions at opposite sides thereof for receiving the threaded portions of said perforate section.

70. 10. Apparatus according to claim 2 wherein said ves-

sel comprises a fluid pressure-tight tank having a greater height than width and having a closable filler opening at the top thereof for placing granular material within said tank, and a closable air vent means at the top thereof for permitting the escape of air from said tank to permit filling of the same with liquid from said perforate pipe section, and a drain opening at the bottom of said tank,

said passage means comprising a branch passage section branching from the primary passage means upstream from said perforate pipe section and rejoining said primary passage means downstream from said perforate pipe section whereby a portion of the flow through said passage means bypasses said perforate section,

valve means in conjunction with said branch section and said perforate pipe section for regulating the proportion of the total flow passing through said branch and perforate pipe sections,

said source of pressure fluid including a pump upstream from said perforate and branch pipe sections, a nozzle at the outlet of said passage means,

a granular material at least partially filling said tank, a liquid of less density than said granular material within said tank and under a pressure corresponding to the liquid pressures within said liquid pressure system,

perforations in said perforate pipe section having greater diameters than the granules within said tank, said perforations being arranged throughout the circumference and throughout the greater portion of the length of said perforate pipe section within said tank.

11. A method of dispensing gritty material in a liquid stream for cleansing and other purposes comprising the steps:

placing a quantity of said gritty material within a pressure-tight enclosure, filling said enclosure with liquid, directing a flow of said liquid under pressure from a

5

10

15

source outside said enclosure along a flow path of substantially constant cross section through and in communication with said gritty material and thence to a point of dispensing outside said enclosure, and during said flow maintaining said enclosure under a liquid pressure approximating the pressure of said flow through said enclosure.

12. A method according to claim 11 including the step:

during said flow separating said flow path from the gritty material within said enclosure with a foraminous material having foramina larger than individual particles of said gritty material so as to control the rate of entrainment of said material in said flow.

13. A method according to claim 11 wherein said liquid flow path is directed through said gritty material in a direction providing a substantially constant liquid pressure head acting on said flow path within said enclosure.

14. Apparatus according to claim 1 wherein said perforate pipe section extends at a generally horizontal disposition through said fluent material and is provided with perforations throughout substantially the entire horizontal extent of said fluent material within said vessel.
